ACOUSTIC FILTER

William C. Zaug, Huntington, N. Y., assignor to Telephonics Corporation, Huntington, N. Y., a corporation of New York

Application January 26, 1951, Serial No. 207,932

6 Claims. (Cl. 181—31)

This invention relates to acoustic filters, and has particular reference to damping and protective filters for telephonic instruments.

The techniques of damping the vibration of a telephonic diaphragm by means of a confined air cushion and acoustic shock protection of telephonic diaphragms by relieving the pressure of a confined air cushion are well known but the duplication of the filter required in each case has been difficult and costly on a production basis because the precision of manufacture of the filter to make it effective has required much hand work as well as time for testing and adjustment and even then the percentage of rejected parts due to imperfect filter manufacture has been disproportionately high.

Inasmuch as both damping and shock protective types of acoustic filters depend upon flow of confined air through an orifice, the orifices must be the proper size and as the orifices are usually small in area, the normal manufacturing tolerances afford too wide a variant to produce the correct orifice area, and the requisite close tolerances are impractical for quantity manufacture. Accordingly, recourse has frequently been had to the expedient of reducing the effective areas of larger orifices by covering them with fine screens or plugging them with fibrous filtering material, but both the screen and filtering material absorb or entrain moisture in use to a degree such that the effective orifice area varies and consequently the acoustic filter characteristics change and are uncertain.

In accordance with the present invention, an acoustic filter and the method of making the same are provided, wherein the air flow orifice of the filter is always of the proper precise area regardless of the number of telephonic units that are produced embodying the filter, and without requiring the use of uncertain added damping means such as screens, fibrous material, and the like.

In a preferred embodiment of the invention, one wall of the confined air cushion chamber at one or both sides of the diaphragm is provided with a louvre-like slot stamped through the said wall by means of a die which is precisely made for that purpose. Preferably, the louvre-like slot has the same orifice width for the acoustic filters of numerous different types or sizes of telephonic devices requiring acoustic damping or acoustic shock protecting means, and the effective orifice area required for each type or size is simply accommodated by varying the length of the slot.

It will be seen that the acoustic filter and the method of making the same, according to the present invention, is simple but very precise and still can be reliably reproduced innumerable times without variation, subject only to wear of the die, and is immune to climatic, atmospheric, or other changes in environment, so that its acoustic characteristics do not change.

For a more complete understanding of the invention, reference may be had to the accompanying drawings, in which:

Figure 1 is the front view of a typical microphone unit embodying the acoustic filter of this invention;

Figure 2 is an axial section therethrough, as seen along the line 2—2 of Figure 1;

Figure 3 is an enlargement of a portion of the front plate section shown in Figure 2, and illustrates a detail of the louvre-like slot therein;

Figure 4 is an axial section through a typical telephone handset receiver unit embodying the acoustic filter of this invention; and

2

Figure 5 is an enlarged section through the filter as seen along the line 5—5 of Figure 4.

Referring to Figures 1 and 2, and understanding that the microphone depicted thereby merely illustrates one form of a typical telephonic device in which the invention may be utilized to advantage, numeral 10 designates the recessed electrode forming with the dome 11 of the thin diaphragm 12, centering washer 13 and filling cap 14, the carbon granule cavity 15. Overlying the diaphragm 12 but spaced therefrom by spacing ring 16 is the rigid front plate 17 forming with the diaphragm 12 and spacing ring 16, an air chamber 18. Spacing washers 19 complete the assembly which is unified by a ring 20 whose crimped or spun over edges clamp the assembly together.

In order that sound waves may impinge on the diaphragm 12 to enable the diaphragm 12 to respond to speech and accordingly actuate the carbon granules in cavity 15 the front plate 17 is vented in some way, usually by perforations of some kind. However, the perforate area frequently is regulated to afford air damping of the vibration of the diaphragm and also to preclude rupture or other injury to the thin, foil-like diaphragm due to sudden transient pressure shocks such as gun blasts, of which the blast from guns on the order of five inch, 25 and 38 calibre is likely to be the most severe. Accordingly, the diaphragm 12 must be protected from such transient blasts by an acoustic filter such as an opening in the front plate 17 of an effective area such as to filter out the sound waves of that magnitude.

The gun blast filter according to this invention is made by stamping a slot 21 in the front plate 17 having the louvre-like shape shown in detail in Figure 3. In the typical case under consideration, the slot 21 has an effective width of 0.003 inch and a length of 0.375 inch, giving an effective area of 0.001125 inch.

The dies forming the slot 21 in sheet metal front plate are combination shearing and forming dies having the contours and the dimensions shown in phantom in Figure 3. Thus, assuming that the diaphragm 12 is 0.020 brass sheet in the illustrative case, the flat working face of the male die 22 is provided with a wedge-shaped shearing tongue 23 having a length of 0.376 inch, a height of 0.023 inch, a base width of 0.040 inch, and a tip width of 0.010 inch, as shown, with a suitable draft dimension for the shear face to permit separation of the die 22 from the flange or louvre-like stamping 24 without deformation of slot 21 thereof and consequent variation of the effective area of the slot 21. The female die 25 conforms to the other side of the louvre-like stamping 24 as shown.

In operation of the filter of Figure 3 as a gun blast filter for a microphone such as is illustrated in Figures 1 and 2, the slot 21 offers a high impedance to the transient gun blasts which would ordinarily destroy the instrument by blowing in the diaphragm 12. This high impedance slot 21 thus limits the air pressure rise in the diaphragm cavity 18 to a point below the rupture pressure of the diaphragm 12 so that the latter is protected.

As indicated, the slot 21 may perform the function of acoustically damping the vibration of a diaphragm, such as the diaphragm of a telephone receiver. As an example, Figure 4 shows the louvre-like slot of this invention utilized in a typical telephone handset receiver comprising a cup-like casing 30 containing the permanent magnet 31, voice coil 32 whose pole shoes are spaced from the imperforate diaphragm 33 clamped at its periphery between the rim of the casing 30 and spacing ring 34 and overlain by a perforate cap 35 held in place by clamping ring 36.

Air-tightly cemented at its periphery to a shoulder 37 in the casing 30 and sealed around coil 32 is a baffle plate 38 forming with the diaphragm 33 and the encircling rim of casing 30, the air chamber 39. The baffle plate may be made of phenolic resin or other relatively rigid non-magnetic material and is provided with an opening 40 having the counterbore 41 in which is cemented the acoustic filter disc 42 as is shown in enlarged detail by Figure 5.

Disc 42 may be of 0.005 inch soft brass and is provided with the louvre-like slot 43 formed therein by a

punching die, which may simultaneously stamp the disc 42 and punch the slot 43 therein. The punch forms an 0.0035 inch slit at an angle of 11° under such conditions that the material is shaped to leave the desired 0.003 inch slot 43 which in this case is 0.250 inch long. Although the slot 43 has a different shape than slot 21 of Figure 3, it performs the same acoustic filtering function and shows that the particular shape of the slot is not fixed, but may have various shapes, as long as its dimensions are correct and are repeated in production without change according to the invention.

In operation of the acoustic filter of Figure 5 as an acoustic damper in the handset receiver of Figure 4, for example, the slot 43 has the effect of regulating the air pressure in diaphragm cavity 39 so that the amplitude of the primary resonant peak of the diaphragm 33 is reduced and a substantially flat response over the voice frequency range results. By electrical analogy, the effect is similar to introducing a resistive component into a resonant circuit, where the resonant element would be analogous to the diaphragm 33 at its natural frequency.

Although several preferred embodiments of the invention have been illustrated and described herein, it is to be understood that the invention is not limited thereby but is susceptible of changes in form and detail within the scope of the appended claims.

I claim:

1. In an acoustic filter for telephonic instruments having a casing containing a diaphragm for receiving or emitting sound waves, the combination of a wall forming a confined air chamber with said diaphragm, and spaced deformations in said wall forming a single slot of predetermined dimension for restricting the movement of air in said confined chamber, the said spaced deformations being respectively disposed along the entire lengths of the longitudinal edges of the slot, with the mutual spacing of the deformations defining the slot area.

2. In an acoustic filter for telephonic instruments having a casing containing a diaphragm for receiving or emitting sound waves, the combination of a wall forming a confined air chamber with said diaphragm, and a louvre-shaped deformation in said wall forming a slot of predetermined dimension for restricting the movement of air in said confined chamber, said deformation in the wall being integral with the wall along the entire length of the slot, thereby to define a single slot.

3. In an acoustic filter for telephonic instruments having a casing containing a diaphragm for receiving or

5
10

emitting sound waves, the combination of a wall forming a confined air chamber with said diaphragm, and a deformed portion on said wall forming a slot of predetermined dimension for restricting the movement of air in said confined chamber, said slot being longer than it is wide and said deformed portion being substantially rectangular and formed integrally with the wall along the entire length of only one side of the slot, the narrow dimension of said deformed portion forming an angle with the plane of the wall.

4. In an acoustic filter for telephonic instruments having a casing containing a diaphragm for receiving or emitting sound waves, the combination of a wall forming a confined air chamber with said diaphragm, and a single deformed slit in said wall forming a single slot of predetermined dimension for restricting the movement of air in said confined chamber.

5. In an acoustic filter for telephonic instruments having a casing containing a diaphragm for receiving or emitting sound waves, the combination of a wall forming a confined air chamber with said diaphragm, said wall having a single slit, and a deformed longitudinal edge of said slit forming with the opposite edge of said slit a narrow slot of predetermined dimension for restricting the movement of air in said confined chamber.

6. In an acoustic filter for telephonic instruments having a casing containing a diaphragm for receiving or emitting sound waves, the combination of a wall forming a confined air chamber with said diaphragm, a deformable portion in said wall, and a single deformed slit through said portion forming a single slot of predetermined dimension for restricting the movement of air in said confined chamber.
